ATTYS.

UNITED STATES PATENT OFFICE.

ERNEST D. PORTER, OF LOS ANGELES, CALIFORNIA.

VENTILATING-DEFLATOR.

1,273,665.

Specification of Letters Patent. Patented July 23, 1918.

Application filed October 23, 1916. Serial No. 127,139.

To all whom it may concern:

Be it known that I, ERNEST D. PORTER, a citizen of the United States, residing at Los Angeles, in the county of Los Angeles 5 and State of California, have invented new and useful Improvements in Ventilating-Deflators, of which the following is a specification.

My invention relates to a rectal venti- 10 lating deflator.

It is an object of this invention to provide a device simple in construction and inexpensive of manufacture to be used in the treatment of cases of flatulency and consti- 15 pation. The device comprises a hollow tube, closed at both ends, and provided with ventilating apertures at the ends, which is inserted in the rectum, affording a constantly open passage to gases generated in 20 the intestinal canal. The outer enlarged end is provided with a removable cap whereby the interior of the device may be easily cleaned and kept in a sanitary condition.

25 My invention consists in the construction and arrangement of parts hereinafter described and claimed.

In the accompanying drawings forming a part of this specification, I have shown a 30 practical embodiment of my invention, and in which:

Figure 1 is an elevation of the device.

Fig. 2 is a vertical cross section taken on line 2—2 of Fig. 1.

35 Fig. 3 is a horizontal cross section taken on line 3—3, Fig. 1.

Fig. 4 is an elevation of a modification of the invention.

40 Fig. 5 is an elevation of another modification of the invention, and Fig. 6 is a section taken on line 6—6, Fig. 5.

The deflator comprises a tubular body 10 cylindrical in shape, provided at one end with a slightly enlarged head 11, spherical 45 in shape. At the other end an enlarged gas discharge chamber 12 is provided which is formed by an upper section 13 having an internal screw thread in which a lower section 14 is screw threaded. The two sections form a smooth joint. The enlarged gas chamber serves also as a retaining shoulder to maintain the device in proper position. At the under face of the lower section 14, and coaxial with the tube 10, is

a square boss or lug 15, whereby the lower 55 section may be easily unscrewed.

A plurality of apertures 16 are provided in the head 11. Similar apertures 17 are provided in the upper section 13 of the gas discharge chamber 12.

60 In the use of the device, a lubricant such as oil, is preferably applied to the head and tube prior to its insertion in the rectum. The device is preferably used during the night, though the same may be used and 65 retained in the rectum during the day, as very little inconvenience in retaining the device is experienced. I have found the following dimensions to give good results: 70 3½ inches, total length, with a diameter of 70 the tube of ½ inch. Any suitable material, such as hard rubber, metal or the like may be used in the construction. The gases generated in the intestinal canal are gradually 75 and constantly vented through my device, relieving flatulency and constipation. By unscrewing the lower section 14 of the gas discharge chamber, access to the interior 80 of the device for cleaning purposes may be had.

85 In the modification shown in Fig. 4, the tubular section 10' is given a slight helical twist. This shape of the tube has the advantage of being more firmly held in position by the muscles of the rectum.

By making the device of metal, electric treatment may be combined with the normal function of the device by connecting the same to a source of electric energy.

In Figs. 5 and 6 I have shown still another modification in which a helical groove 18 having rounded edges is provided on the periphery of the tubular member 10. The groove 18 allows the muscles of the rectum to grip the device and to hold the same 95 in place.

I claim:

1. In a device of the character described, the combination of a rigid cylindrical tube having a perforated head at one end, and 100 an enlarged perforated gas chamber at the other end, said chamber constituting a tube retaining shoulder, and comprising an upper section fast to said tube, and a lower section screw threaded on said upper sec- 105 tion, and a lug depending from said lower section whereby said lower section may be operated.

2. In a device of the character described, the combination of a rigid cylindrical tube having a perforated head at one end, and an enlarged perforated gas chamber at the other end, said chamber constituting a tube retaining shoulder, and comprising an upper section fast to said tube, and a lower section screw threaded on said upper section.
- 10 3. In a device of the character described, the combination of a rigid cylindrical tube having a perforated head at one end, said tube having means on the periphery thereof, whereby the same may be held in operative position, and an enlarged perforated gas chamber at the other end, said chamber constituting a tube retaining shoulder, and comprising an upper section fast to said tube, and a lower section screw threaded on said upper section.
- 15 4. In a device of the character described, the combination of a rigid cylindrical tube having a perforated head at one end, said tube being provided with a helical groove on the periphery thereof, and an enlarged perforated gas chamber at the other end, said chamber constituting a tube retaining shoulder, and comprising an upper section fast to said tube, and a lower section screw threaded on said upper section.

comprising an upper section fast to said tube, and a lower section screw threaded on said upper section.

20

4. In a device of the character described, the combination of a rigid cylindrical tube having a perforated head at one end, said tube being provided with a helical groove on the periphery thereof, and an enlarged perforated gas chamber at the other end, said chamber constituting a tube retaining shoulder, and comprising an upper section fast to said tube, and a lower section screw threaded on said upper section.

25

In testimony whereof I have signed my name to this specification.

30

ERNEST D. PORTER.
